UNITED STATES PATENT OFFICE.

GEORGE W. FRANZHEIM, OF PITTSBURGH, PENNSYLVANIA.

HEATING APPARATUS.

1,139,660.

Specification of Letters Patent. Patented May 18, 1915.

Application filed July 9, 1914. Serial No. 850,012.

To all whom it may concern:

Be it known that I, GEORGE W. FRANZHEIM, a citizen of the United States of America, residing at Pittsburgh, in the county of Allegheny and State of Pennsylvania, have invented certain new and useful Improvements in Heating Apparatus, of which the following is a specification, reference being had therein to the accompanying drawing.

This invention relates to a furnace for heating water or generating steam and for consuming smoke during the water heating operation, and has for its principal objects the provision of a heating furnace wherein a combustion chamber having the down draft principle of combustion is provided with a direct passage for the products of combustion thereby facilitating the combustion of the fuel; the provision of a water heating element which offers a minimum of resistance to the passage of the gases or products of combustion and which may absorb a maximum quantity of heat from the gases passing them; the provision of an arrangement of water heating elements with respect to the fire box whereby the high temperature of the gases contacting with the water heating elements will cause the soot deposits which accumulate thereon to scale off by virtue of an increased expanding and contracting action; the provision of a construction wherein the parts are readily assembled and repaired, and the provision of a construction that is simple and strong and durable as well as embodying a high degree of efficiency.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the general views:—

Figure 1 is a longitudinal sectional view

of a furnace in accordance with this invention.

Figure 2 is an end elevation partly in vertical section, and

Figure 3 is a transverse sectional view.

Referring to the drawings, the furnace consists of a series of vertically disposed abutting units 4, 5, 6, 7, 8, 9, 10, 11, 12, 13 and 14 which are supported upon a base 60 formed of a pair of channel irons 15 and 16.

Each of the units 5 to 13 consists of a pair of vertically disposed hollow legs 17 connected together at their top by a horizontally disposed hollow leg 18, and the side 65 walls of each horizontal leg 18 is offset as at 19 and provided centrally with a circular opening 20. The openings 20 of the horizontal legs 18 of the units 5 to 13 aline with each other.

The legs 17 of the units 5, 6, 7 are connected together by horizontally disposed hollow integral grate bars 21.

The vertical legs 17 of the unit 8 are connected together by a horizontally disposed 75 hollow integral grate bar 22, which has formed integral therewith a vertically disposed hollow plate 23, the latter being also integral with the legs 17 of the unit 8 and with the bottom of the horizontal leg 18 of 80 the unit 8.

The grate bars 21 and 22 are positioned intermediate the ends of the legs 17 of the units 5 to 8 and in connection with the legs 17, 18 and plate 22 provide an upper fire 85 box indicated by the reference character 24.

The units 5 to 8 are arranged in abutting engagement and are interposed between the units 4 and 9, the former being arranged at the front of the furnace and consisting of a 90 vertically disposed hollow rectangular casting formed with an opening 25, which constitutes a fire box opening and which is closed through the medium of a door 26. Supported between the channel bars or irons 95 15 and 16 are horizontally disposed grate bars 27, which are arranged at the bottoms of the legs 17 of the units 5 to 8 and provide in connection with the legs 17 of the units 5 to 8, a lower fire box 28. The unit 4 below 100 the opening 25 is formed with an opening 29, which constitutes an entrance to the

lower fire box 28, and said opening 29 is closed by a door 30.

The vertical legs 17 of the units 9 to 13 are connected together at their lower ends by 5 horizontally disposed integral hollow legs 31, and the said legs 31 of the units 9 to 13 are connected to the horizontal legs 18 of the said units by vertically disposed spaced tubes 32, these latter opening at one end into 10 the legs 18 and at their other ends into the legs 31.

The unit 14 which is arranged against the unit 13 and at the rear of the furnace consists of a rectangular casting 33 formed with 15 an opening 34, which constitutes an outlet for the products of combustion.

The vertical legs 17 of the units 5 to 13 at their lower ends are enlarged as at 35 and extending through the said enlarged 20 portions are tie bolts 36, these latter also extend through the units 4 and 14.

Extending through the units 4 and 14 at the top thereof and through the openings 20 formed by the units 5 to 13 is a tie bolt 37, 25 which carries on each end a clamping member 38, and the said members 38 abut against and extend into the units 4 and 14. The tie bolts 36 carry on each end clamping members 39 which abut against and extend into 30 the units 4 and 14. The furnace is provided with a suitable water inlet, as well as a suitable hot water outlet.

The fire in the lower fire box 28 is employed for consuming the smoke as it passes 35 down between the grate bars 21 and 22, and the fire in the box 24 is utilized primarily for heating the water which is arranged in the water space formed by the hollow units 4 to 14.

40 The tubes 32 are so spaced as to not interfere with the passage of the heating units from the fire boxes 24—28.

The advantages incident to the design and relative arrangement of the various elements constituting the combined furnace and heating apparatus hereinafter appears.

The provision of a fire box surrounded on all sides by hollow walls containing the water to be heated together with hollow 50 water tube grate bars communicating with the hollow walls of the fire box, greatly increases the heating capacity of the apparatus, and the use of the down draft grate in combination with a lower up draft grate 55 insures almost perfect combustion of the fuel as well as of the smoke resulting from such combustion.

The heating chamber which consists of water filled walls provided with a battery 60 of vertical water tubes communicating with the top and bottom walls, located behind the fire box so that the lower ends of the tubes are behind the smoke passage of the furnace, while the smoke exhaust is placed in the

rear walls of the chamber adjacent the top 65 of the tubes, provides a very efficient water heating element for the following reasons. The hot gases strike the coolest portion of the water tubes first, and as the gases pass diagonally across the heating chamber from 70 the smoke passage in the furnace to the exit near the top, they are buffeted by the vertical tubes as they pass them transversely thereby causing a greater number of heated 75 gas particles to come in contact with the vertical tubes than would be the case if the gases passed along parallel with the tubes.

The gases have a direct passage from the fire box to the exhaust flue thereby insuring an unimpeded draft, a condition not found 80 in a furnace having a return flue and a condition necessary for the successful operation of a down draft combustion grate.

The water tubes being vertically disposed and in contact with extremely hot gases are 85 continually contracting and expanding, such action causing the soot deposits thereon to scale off and fall from the tubes insuring at all time water tubes free from soot, thus obviating the necessity of frequent cleaning 90 and affording a better heat absorbing unit.

What I claim is:—

1. A heating apparatus having at its front end a furnace portion, and at its rear end a boiler portion, the furnace portion 95 comprising a down draft grate, a lower up draft grate beneath the down draft grate and an outlet for the gases at the rear of and between the grates; the boiler portion including a water heater or boiler consisting of a heating chamber provided with hollow top and bottom walls for containing water, a battery of vertical water tubes connecting the bottom wall of the heating chamber with the top wall, and an exhaust 100 for the gases through the rear wall of the heating chamber adjacent the top thereof arranged so the gases from the furnace will 105 diagonally traverse the heating chamber from the bottom thereof toward the top and transversely engage the vertical water tubes, the said bottom wall lying at a level adjacent that of the lower grate.

2. A heating apparatus having at its front end a furnace portion and at its rear 115 end a boiler portion, the furnace portion comprising a down draft grate, a lower up draft grate beneath the down draft grate and an outlet for the gases at the rear of and between the grates; the boiler portion including a water heater or boiler consisting of a heating chamber provided with hollow top and bottom walls for containing water, a battery of vertical water tubes connecting the bottom wall of the heating chamber at a point below the down draft 120 grate, with the top wall of the heating chamber above the down draft grate and an

exhaust for the gases through the rear wall of the heating chamber adjacent the top wall of the heating chamber arranged so the gases from the furnace will diagonally 5 traverse the heating chamber and transversely engage the vertical water tubes.

In testimony whereof, I affix my signature, in the presence of two witnesses.

GEO. W. FRANZHEIM.
